UNITED STATES PATENT OFFICE.

ARTHUR I. CLYMER, OF VAN WERT, OHIO.

DEVICE FOR USE IN VIEWING MOTION PICTURES.

Application filed August 9, 1923. Serial No. 656,525.

To all whom it may concern:

Be it known that I, ARTHUR I. CLYMER, a citizen of the United States of America, and a resident of Van Wert, in the county of Van Wert and State of Ohio, have invented a new and Improved Device for Use in Viewing Motion Pictures, of which the following is a description.

My invention relates to a device for use 10 in viewing motion pictures and has for an object to provide a device that will prevent injury to the eye by eliminating or minimizing the strains incident to such pictures.

More specifically, the invention has for objects to provide a device that may be reversed to view the pictures from either end of the device, the opposite ends being differently formed to adapt it to people wearing 20 glasses or adapted to more closely conform to the face when glasses are not worn.

The invention furthermore has for an important object to provide a device that may be folded into compact form to occupy 25 small compass, whereby the device may be conveniently accommodated in a pocket.

The invention also has in view to provide a device for the indicated purpose reflecting practical considerations with respect to 30 strength with lightness and simplicity of construction.

The nature of the invention and its distinguishing features and advantages will clearly appear as the description proceeds.

Reference is to be had to the accompanying drawings forming a part of this specification, it being understood that the drawings are merely illustrative of practical examples of the invention.

Figure 1 is an elevation of a device for viewing motion pictures representing my invention in one form;

Figure 2 is a transverse vertical section on a reduced scale, the plane of the section being indicated by the line 2-2 in Figure 3;

Figure 3 is a plan view of the device enlarged over the showing in Figures 1 and 2;

Figure 4 is a section at right angles to 50 Figure 2 as indicated by the line 4-4 in Figure 3;

Figure 5 is a view similar to Figure 1 illustrating another form of the invention;

Figure 6 is a plan view of the device 55 formed as in Figure 5;

Figure 7 is an elevation showing the invention in still another form.

Referring at first more particularly to the invention as illustrated in Figures 1 to 4, the device comprises two optical tubes 10 connected in this form of the invention by rigid cross bars 11. A handle 12 is provided and pivoted at its upper end as at 13 to a keeper device designated generally by the numeral 14 and presenting a seat 15 and clamp 16 at right angles to each other, the former disposed at the top of the adjacent tube 10, said clamp extending vertically. The handle part 12 can thus swing on the pivot 13 from a vertical position seated in the clamp 16 as shown in Figure 1 to a horizontal portion on top of the tubes 10 extending across the same as shown in Figures 3 and 4. A second keeper 17 is provided on the second tube 10 of a pair 70 aligned with seat 15 to coact in holding the handle part 12 in folded or knocked down position. In connection with the handle part 12 is an extension handle section 18 detachably secured by any suitable means to the handle part 12, the latter being shown as having a socket 19 to detachably receive the upper end of the section 18. Both the handle part 12 and the handle section 18 are advantageously tapered. In order to 75 hold the handle section 18 when the device is assembled in knocked down form, I provide a tubular holding device 20 rigid with the tubes 10 and bridging the same parallel with seat 15 and keeper 17 into which 80 device 20 the handle section 18 may be inserted when detached from the handle part 12.

At one end 21, the two tubes 10 terminate in the same transverse plane so that the pictures may be viewed through the said end 21 by those wearing glasses. At their opposite ends the tubes 10 have curved end surfaces 22 conforming approximately to the facial formation adjacent the eyes. A person without glasses may thus view the pictures through the curved ends 22 and with the optical tubes close to the face.

In the form shown in Figures 5 and 6 the optical tubes 110 are united by the same 105 cross bars 11 and are formed with plane ends 21 and curved ends 22. In this form of the invention a unitary handle part 112 is provided which is tapered and adapted at its smaller end to enter a vertical sleeve 110

116 disposed vertically and made rigid with the adjacent tube 110. At the top of the device parallel with the tubes and preferably adjacent to one tube 110 is a second keeper sleeve 115 to receive the handle part 112 when removed from the keeper sleeve 116.

In the form shown in Figure 7 the optical tubes 110 are the same as in the other two forms and with this form of the invention sleeves 115, 116 are provided on one tube. The tubes, however, are pivotally connected by any approved means. I have indicated conventionally tubes connected after the manner of opera glasses, the cross bars 111 being united as at 23 so that the tubes 110 may be swung on the pivot to vary the pupillary distance as for example in adjusting the device to suit either a child or an adult.

I would state in conclusion that while the illustrated examples constitute practical embodiments of my invention, I do not limit

myself strictly to the exact details herein illustrated, since, manifestly, the same can be considerably varied without departure from the spirit of the invention as defined in the appended claims.

Having thus described my invention, I claim:

1. A device for use in viewing motion pictures, comprising optical tubes, a handle comprising separable sections, means to dispose the handle adjacent the side of one of the tubes and in a plane perpendicular to the plane in which the axes of the tubes lie, means to hold separately the handle sections on the tubes when the device is in knocked down form.

2. A device of the class described comprising optical tubes, a handle, and handle receiving keeper sleeves rigid with the tubes and approximately at right angles to each other.

ARTHUR I. CLYMER.
